UNITED STATES PATENT OFFICE.

GEORGE R. RICH, OF CHICAGO, ILLINOIS, ASSIGNOR TO THE GEO. R. RICH MANUFACTURING COMPANY, OF CHICAGO, ILLINOIS, A CORPORATION OF ILLINOIS.

CHUCK.

SPECIFICATION forming part of Letters Patent No. 772,534, dated October 18, 1904.

Application filed November 28, 1902. Serial No. 133,004. (No model.)

To all whom it may concern:

Be it known that I, GEORGE R. RICH, a citizen of the United States of America, residing at Chicago, in the county of Cook and State 5 of Illinois, have invented certain new and useful Improvements in Chucks, of which the following is a specification.

My invention relates to certain new and useful improvements in chucks; and its object is 10 to produce a device of this class which shall be cheaper than the devices of the class heretofore in use, which shall operate as satisfactorily as do other devices in every respect, and which in addition shall be much easier to 15 sharpen for use.

To these and certain minor ends, which will 20 duly appear in the course of the specification, my invention consists in certain novel features of construction clearly illustrated in the accompanying drawings and described in this specification.

In the aforesaid drawings, Figure 1 is an 25 elevation of my improved drill and chuck. Fig. 2 is a section in the line 2 2 of Fig. 1, certain of the parts, however, being shown in elevation. Fig. 3 is a section in the line 2 2 through the main cylinder of the chuck, the remaining parts being removed. Fig. 4 is a similar section of the bushing. Fig. 5 is 30 a section in the line 5 5 of Fig. 2. Fig. 6 is a section in the line 6 6 of Fig. 2. Fig. 7 is an end view of the drill-stop, and Fig. 8 is a perspective of one of the drill-clamping jaws.

Referring to the drawings, A is the main 35 cylinder of the drill-chuck, provided with an internal screw-thread α' and an externally-threaded shoulder α at its lower end. Within the drill-chuck is threaded a drill-stop B in the form of a block, which can be screwed 40 up or down in the interior of the cylinder. The block is provided on its lower surface with a plurality of grooves b of such breadth as to fit the upper end of the drill, so that the drill being held against rotation the block 45 cannot be screwed one way or the other. In the top of the cylinder is a head C, provided with a spindle c , adapted to be centered and secured in a drill-press. The drill proper

(indicated by D) is in the form of a straight bar of uniform cross-section throughout its 50 entire length and is constructed, preferably, of blue chip-steel, bars of which can be obtained on the market. The bars are rounded on their edges at d and provided by grinding with suitable cutting edges d' at their lower ends. The drill proper is placed in the drill-chuck with its upper end in one of the grooves b of the block B. A bushing E, circular in form and of the same internal diameter as the greatest breadth of the drill, is slipped over the 55 drill to center the same. Two jaws F, similar each to each, are then placed in position. The shape of these jaws is clearly shown in perspective in Fig. 8, each consisting of a frusto-conical segment f , a point f' thereon, a portion f'' in the shape of a segment of a cylinder on the opposite side of the frusto-conical segment from the point, and a shoulder f''' . Suitable notches α'' are provided in the wall of the main cylinder A and similar 70 notches e in the wall of the bushing E to receive the shoulders f''' , where they will necessarily be held without rotation with respect to the cylinder A. This being done, the cap G is screwed up over the end of the cylinder, 75 a beveled portion g thereon coming into contact with the frusto-conical portion f of the jaws, forcing them tightly into place, producing great pressure upon the drill proper and wedging it firmly in place. When the drill 80 becomes dull for any reason, the cap G is loosened, the drill is pulled out, the block B screwed down, the drill after grinding pushed in against it, and the cap retightened. The drill can then be used to the very end, the 85 point being merely reground as it becomes dull and the stop being moved up to compensate for the wear.

The advantages of my improved drill can be best set forth by having reference to certain of the types heretofore in use. The drill which heretofore has been most used for rapid work is a drill having a point much like that shown herein, but which is formed by flattening out the end of a cylindrical rod. When, 95 therefore, the point of the drill becomes worn

down, as it of course does after being re-sharpened a few times, all the flattened portion is used up, and it becomes necessary to reforge the entire drill, which of course necessitates retempering and makes it as expensive to sharpen a drill as to construct my new one. With my device, on the other hand, nothing of this sort has to be done, the flat drill proper being merely fed forward as the point is worn down and no treatment but grinding is necessary to keep it sharpened. A further advantage consists in the fact that by using the drill proper of the same cross-section throughout its length certain materials can be used in its construction which cannot be readily forged to form drills of the types heretofore in use.

As above mentioned, the internal diameter of the bushing E is that of the largest diameter of the drill and centers the same. The use of bushing enables different-sized drills to be used in connection with the chuck. When a drill of larger diameter is to be used, a bushing of an equal internal diameter is selected and secured in place in the mouth of the cylindrical casing.

I realize that considerable changes can be made in the details of this construction, and I do not, therefore, desire to limit myself to the exact construction described.

I claim as new and desire to secure by Letters Patent—

1. In a device of the class described, the

combination with a main cylinder, of a stop screw-threaded therein, said stop having a diametrical notch adapted to receive the end of a parallel-faced drill to center the same and being prevented by engagement therewith, from rotation in the chuck, a pair of jaws and means for bringing them together upon the drill.

2. In a device of the class described, the combination with a main cylinder, a cap thereon and a drill-stop movable therein, of a bushing adapted to surround and tightly fit the drill to center the same, suitable jaws and means for bringing said jaws together upon the drill.

3. In a device of the class described, the combination with a main cylinder, and a stop therein, of a bushing adapted to surround and center a drill, the bushing and main cylinder being suitably notched, of jaws provided with shoulders adapted to engage said notches to prevent relative rotation of the parts, and means for closing the jaws upon the drill to hold the same in place.

In witness whereof I have signed the above application for Letters Patent, at Chicago, in the county of Cook and State of Illinois, this 18th day of November, A. D. 1902.

GEORGE R. RICH.
